(57) **CLAIM**

The ornamental design for a desoldering tool, as shown and described.

DESCRIPTION

FIG. 1 is a first perspective view of a desoldering tool;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the desoldering tool in which the design is embodied that are not considered part of the claimed design.

The dashed lines show a borderline between the claimed design and other portion.
